UNITED STATES PATENT OFFICE.

WILLIAM A. HARVEY, OF SCRANTON, PENNSYLVANIA.

PORTABLE ELECTRIC LAMP.

Application filed June 13, 1921. Serial No. 477,097.

To all whom it may concern:

Be it known that I, WILLIAM A. HARVEY, a citizen of the United States, and a resident of Scranton, in the county of Lackawanna and State of Pennsylvania, have invented 5 certain new and useful Improvements in Portable Electric Lamps, of which the following is a specification.

My invention relates to electric lamps and 10 more particularly to simple portable lamps which may be conveniently placed upon desks, tables and the like.

The main feature of importance of my invention is that of providing a lamp of this type wherein there are means for varying the degree of brilliance of the light. In 15 this behalf, my invention is in the nature of an improvement on my Patent Number 1,380,143 granted to me May 31st, 1921.

Portable lamps in which means are provided for regulating the brilliance of the light have proven particularly attractive. It 20 is essential, however, that the means for accomplishing this regulation must be simple, 25 easy to manipulate and in no way affect the efficiency and durability of the lamp. In this behalf, my invention excels in its simplicity.

It is of likewise extreme importance that 30 the assembling of the parts in an article of this type be made comparatively simple and that such parts be made removable should the occasion arise when it becomes necessary to replace one or more of the parts.

It is therefore, an object of my present 35 invention to provide a lamp of the general type illustrated in my patent hereinbefore referred to in which however, the arrangement of the parts is such that the elements 40 which control the regulation of the light current may be assembled as a unit and then properly disposed within the base of the lamp.

In this behalf I provide a circular base 45 plate of suitable dimensions to enable it to be contained within the hollow base of the lamp structure. Upon this base plate I support the resistance coil or element, a series 50 of spring contact members and the associated terminals. These parts can obviously be assembled and thereafter placed within the base of the main structure, thereby simplifying the device considerably from the 55 standpoint of manufacture and enabling this assemblage of parts to be removed when required.

pairs are necessary to any element thereof.

Another feature of this improved structure is that of efficiently providing ventilation for the base of the lamp in which is reposed the resistance element. A certain 60 amount of ventilation is necessary in order to dissipate the heat which is generated when a whole or a part of the resistance element is active.

In this behalf the bottom plate or closure 65 for the open side of the base is stepped and the peripheral section thereof formed with a series of apertures. The top part of the base is likewise apertured and thereby forming a ventilation path which extends from 70 the under side of the lamp upward through the base and out at the top side of the base.

Various other features of structural importance are shown in the accompanying drawing and will be described more fully in 75 the accompanying specification.

In the drawings Figure 1 is a side elevation of the lamp constructed in accordance with my invention.

Figure 2 is an enlarged section of the base 80 portion of the lamp,

Figure 3 is a bottom plan view with the base plate removed,

Figure 4 is a fragmentary separated perspective view of the base of the lamp and 85 assemblage of current regulating parts.

Figure 5 is a section on line 5—5 of Figure 2 looking in the direction of the arrows and

Figure 6 is a diagrammatic view of the 90 circuit employed in this construction.

In Figure 1 the assembled lamp is illustrated and is shown as comprising a base A, a standard or post B which is of decorative configuration, an electric light socket and 95 bulb C and a shade D.

A hollow post 10 extends centrally of the decorative portion B and is screw-threadedly united at its lower end to the base in 100 a manner to be more fully hereinafter described. The base A is formed of a recessed block 11 which may be and is preferably, formed of wood. I have found that the use of balsa wood is particularly advantageous inasmuch as it has an extraordinary 105 low degree of conductivity and hence is effective in insulating the outer surface of the base from the heat which may be generated during the use of the lamp. A metal shell 110 12 of decorative configuration covers the block 11.

The block 11 is formed with a centrally

disposed aperture 13 to permit ingress of the light circuit wires which pass through the post 10 as clearly illustrated in Figure 2. The bottom of the recess formed in the block 11 is cut away centrally thereof to accommodate a ring washer of insulating material 14. Disposed on the top of the block 11 is a supporting spider 15. Flat headed screws 16 pass upwardly through the insulating washer 14 and are threaded into the spider 15 thereby clamping between these two elements the block 11. The spider 15 is provided centrally thereof with a screw-threaded aperture 17 which engages the lower end of the post 10 thereby uniting the upper elements of the lamp structure to the base. The decorative members B may be of a standard type as is the socket member C and it consequently follows that the socket C may be screw-threaded to the upper end of the post 10 and the decorative members B slipped thereon and the whole structure united with the base by screwing the lower end of the post 10 into the spider 15.

A finishing top plate 18 which likewise may be of decorative configuration is disposed centrally of the base and at the top thereof as clearly shown in Figures 1 and 30 2. This top plate has a centrally disposed aperture 19 to permit the passage of the post 10 therethrough and a multiplicity of radially disposed apertures 20 which provide communication to the interior of the base to assist in its ventilation and dissipation of the heat generated therein. This top plate 18 may be formed of any suitable material but herein it is illustrated as formed of wood. Secured to the top plate 18 and at one side thereof is a metal strap 21 held in place preferably by screws 22. A thumb screw 23 engages by reason of its screw-threaded shank 24 with a threaded aperture in the strap 21 and projects through aligned openings 25 and 26 in the top plate 18 and shell 12 respectively. The block 11 is formed with a vertically disposed opening in which is slidably mounted a fiber plug 27. The end of the screw shank 24 is adapted to contact the fiber plug 27 as clearly shown in Figure 2 and upon proper rotation of the thumb screw to move this fiber plug downwardly, for a purpose to be more fully hereinafter described. For uniting the top plate 18 and the shell 12 I provide screws 28 having elongated heads 29. These screws pass upwardly through the shell and are threaded into the top plate 18. The top face of the block 11 is recessed as at 30 in order to accommodate the elongated heads 29 of the screws 28. Thus, when assembling the several parts the block 11 will be properly aligned to enable the thumb screw 23 to operate the fiber plug 27.

65 By referring to Figures 2, 3 and 4, the

assemblage of parts which form the unit for varying the degree of brilliancy of the light will be described. A circular base plate of insulating material 31 is provided of such dimensions as to enable the recess of the block 11 to accommodate the same. Secured at separated radial points to the base 31 are fiber supporting posts 32, which support a resistance coil or element 33. Supporting elements 32 are held in place preferably by flat headed screws 34 which pass through these supporting elements and into the base plate 31. Resistance controlling contacts 35, 36 and 37 are mounted on the base 31, the contact 35 being rigid, the contacts 36 and 37 being resilient. The free ends of these contacts are superposed and register with an opening 38 formed in the base plate 31. The fiber plug 27 is adapted to slide through this opening 38 and engage the uppermost contact 37, which is a spring contact, to cause it to engage contact 36 and thereafter to cause contact 36 to engage contact 35, thus successively cutting out sections of the resistance element. The contact member 35 is rigid so as to limit the movement of spring contacts 36 and 37.

Wires 39 connect the contacts to the resistance coil so that the flow of the current therethrough can be regulated as will be explained more fully hereinafter. Two-wire cord 40 is admitted to the recess of the block 11 through an aperture 41 formed in one side thereof and the base plate 31 is cut away as at 42 to accommodate this cord. A strain resistance element in the form of a block of insulation 43 is secured to the base plate 31 by screws 44 and provided with apertures for the wires of the cord 40 as is clearly illustrated in Figures 3 and 4. These wires are snubbed around the ends of the block 43, one wire being connected to spring contact 37 and the other to a plate 45, which carries a terminal 46 for one of the wires 47 which leads to the light. The other wire 47 is connected to terminal 48 carried by contact 35.

For retaining the base plate 31 within the recess of the block 11 I provide screws 49, preferably three in number which project upwardly through the base plate 31 and are screwed into threaded apertures 50 formed in the ring washer 14. Thus after assemblage of the several parts just described, the base plate 31 and the several parts carried thereby can be positioned in the recess of the block 11 and retained there by these screws 49.

As hereinbefore stated, the bottom of the base is open and for closing this opening there is provided a cover plate 51 shouldered circumferentially as clearly illustrated in Figures 1 and 2, to provide a pedestal portion 52. Arranged radially of the cover 51 and near the periphery thereof, there are a

multiplicity of apertures 53 which cooperate with the apertures 20 formed in the top plate 18 for affording ventilation to the base of the lamp.

5 A strut 54 is disposed across a central aperture 55 formed in the base plate 31 and is secured in place at one end by the screw 49 which engages a semi-circular depression 56 formed in the end of the strut 54. The 10 other end of the strut has a hook-shaped end 57 which engages a screw 58. Rigidly projecting from the strut 54 is a screw-threaded shank 59. This shank 59 projects through an aperture formed in the cover plate 51 as 15 clearly shown in Figure 2. The cover plate is formed with a centrally disposed depression in which is lodged a washer 60 and a nut 61 screwed on the screw-threaded shank 59 and holds the cover plate 51 in place. The 20 strut 54 is obviously removable, thus permitting access to the wires 47 during the assembling of the parts of this device.

In order to eliminate the danger of sparks which might be caused by short circuiting of the several wires within the base from escaping therethrough, I provide sheets of perforated material 62 and 63 disposed above and below the base plate 31 respectively. This material is preferably fine mesh wire netting and the sheet 62 is held in place by the washer 14 while the sheet 63 is clamped between the block 11 and the cover 51. Obviously the sheet 62 is apertured centrally thereof to permit passage of the wires 47 therethrough.

35 In Figure 6 I have diagrammatically illustrated the wiring circuit employed in this device. Positive and negative wires E and F are connected to a suitable source of current. Current flows through positive wire E to point G, thence through resistance 33 through wire 46^a to the light, then returning through the negative wire F.

Assuming that the thumbscrew 23^a has 45 been rotated to cause plug 27^a to be depressed effecting a contact between contact members 37^a and 36^a the circuit will be as follows: From wire E to terminal G, through contacts 37^a and 36^a to point H, 50 thence through the remaining portion of the resistance 33^a, through wire 46^a to the light and then to the negative wire F.

Finally when thumb screw 23^a has upon 55 further manipulation caused the fiber plug 27^a to effect a contact between contacts 36^a and 35^a the circuit is as follows: from the positive wire E to terminal G then through contacts 37^a, 36^a and 35^a to terminal K, then through wire 46^a to the light and thence to 60 the negative wire.

It is quite obvious from the foregoing description that rotation of thumb screw 23^a causes successive engagement of the contacts which engagement cuts out sections of the 65 resistance. When the contacts are in the

position illustrated diagrammatically in Figure 6, the entire resistance is in circuit with the light and hence this light burns with its least degree of brilliancy. When the contacts are all in engagement one with another, the resistance element is out of the circuit and the light burns at its highest degree of brilliancy.

The advantages of a structure such as described and illustrated herein will be readily apparent to those skilled in the art. A lamp having the advantages of durability is provided, with however, the added advantage of light regulation. The parts which effect this light regulation are concealed from view and contained in the base of the lamp which is not noticeably larger than standard lamps of this type which are now on the market.

Further outstanding advantage of this 85 invention resides in the fact that the several elements which control the brilliancy of the light may be assembled separately from the lamp and then inserted therein. In this behalf it should be noted that the strut 54 90 is removable and is to be positioned upon the base plate 31 after this base plate has been secured in position and the wires which lead to the light have been properly connected to their terminals. The strut 54 95 after being secured to the base plate then affords means for attaching the cover 51.

The shouldered cover 51 raises the base sufficiently from the table or the like upon which it is placed so as to permit air to enter 100 the ventilating openings 53 and to pass around the resistance element 33 and then out through the openings 20 formed in the cover plate 18. This ventilation effectually dissipates the heat which naturally results from activity of the resistance element. 105 As stated hereinbefore, the body or block 11 is preferably made of wood, although in some instances other material whose heat conductivity is low might be employed. As 110 also stated hereinbefore, I have found it particularly advantageous to employ balsa wood, thereby effectually insulating the exterior of the lamp base from the heat of the coil.

115 While the details of construction illustrated in the drawings and described hereinbefore have proved by actual tests to be efficient and desirable, I do not wish to be unnecessarily limited, but specifically reserve 120 the right to make such changes and modifications as come within the purview of the accompanying claims.

Claims:

1. A portable electric light fixture comprising a base, a vertical support projecting therefrom, an electric light socket and bulb carried by said support, a circuit for said electric light bulb, said base comprising an open-sided recessed block, a metal shell cov- 125
130

- ering said block, a removable unit adapted to be disposed in said recess comprising a circular plate of insulating material, a resistance coil secured to said plate, a set of superposed contact members carried by said plate, means for removably securing said plate within said recess, a fiber plug slidably supported within said block and adjacent said contacts, a thumb screw mounted upon said base and operatively engaging said plug for causing the same to effect engagement of said contacts, said resistance coil and contacts being connected in said electric light circuit and a cover for closing the open side of said recessed block and means carried by said plate for removably securing said cover in place.
2. A portable electric light fixture comprising a base, a support projecting vertically therefrom, a socket and electric light bulb carried by said support, a circuit for said electric light bulb, said base comprising a recessed wooden block open at the bottom thereof, a metallic shell covering said wooden block, a top plate for said base, a removable unit for controlling the degree of brilliance of said light comprising a circular plate of insulating material, a resistance coil carried thereby, a set of contacts electrically connected to said resistance coil, said resistance coil and contacts being included in said electric light circuit, a fiber plug slidably mounted in said wooden block and positioned so as to engage said contacts, a thumb screw mounted on said top plate and operatively engaging said fiber plug, screws for securing said top plate to said metallic shell, said screws being provided with elongated heads, cooperating recesses formed in the top face of said wooden block whereby said screw heads and recesses cooperate to properly align said shell and top plate with said wooden block, a cover for the open side of said recess and means carried by said insulating plate for removably securing said cover in place.
3. A portable electric light fixture comprising a base, a support projecting from said base, an electric light socket and electric light carried thereby, a circuit for said electric light, said base being formed of a wooden block provided with a recess open at one side, a metallic shell covering said wooden block, a top plate secured to said shell and forming a part of said base, a removable plate secured within said recess, a resistance coil carried by said plate, a set of contact members electrically connected to said resistance for controlling the same, said contacts and resistance element being connected to said electric light circuit, means carried by said top plate and wooden block and operable from the top side of said base for causing the successive engagement of said contacts, a cover for closing
- said recess, a strut carried by said removable plate, means projecting from said strut for removably securing said cover plate in position, said top plate and cover plate being provided with a multiplicity of apertures for ventilating the interior of said base.
4. A portable electric light fixture comprising a base, a support projecting therefrom, an electric light socket and bulb carried by said support, a circuit for said electric light, said support being formed of a pipe, the wires of said electric light circuit passing through said pipe, said base being formed of a recessed block open at its bottom side, a metallic shell covering said base, a top plate secured to said shell, said wooden block being provided with a central aperture communicating with said recess, a spider spanning said aperture at the top of said block, a ring of insulating material surrounding the edge of said aperture at the bottom of said recess, screws passing through said ring of insulating material, said wooden block and into said spider for clamping said insulating ring and spider to said wooden block, means for screw-threadedly uniting the lower end of said pipe and said spider, a removable element disposed within said recess, said removable element comprising a circular plate of insulating material, a resistance coil carried thereby, a set of contacts for controlling said resistance, said contacts and resistance coil being electrically interconnected and connected to said electric light circuit, screws passing through said plate and into said insulating ring for removably securing said plate within said recess, a shouldered cover plate for closing the open side of said recess, a removable strut carried by said plate and means projecting from said strut for removably securing said cover plate in position.
5. A portable electric light fixture comprising a base, a support projecting therefrom, an electric light socket and bulb carried by said support, a circuit for said electric light, said support being formed of a pipe, the wires of said electric light circuit passing through said pipe, said base being formed of a recessed block open at its bottom side, a metallic shell covering said base, a top plate secured to said shell, said wooden block being provided with a central aperture communicating with said recess, a spider spanning said aperture at the top of said block, a ring of insulating material surrounding the edge of said aperture at the bottom of said recess, screws passing through said ring of insulating material, said wooden block and into said spider for clamping said insulating ring and spider to said wooden block, means for screw-threadedly uniting the lower end of said pipe and said spider, a removable element disposed within said recess, said removable element comprising a

circular plate of insulating material, a resistance coil carried thereby, a set of contacts for controlling said resistance, said contacts and resistance coil being electrically interconnected and connected to said electric light circuit, screws passing through said plate and into said insulating ring for removably securing said plate within said recess, a shouldered cover plate for closing 10 the open side of said recess, a removable

strut carried by said plate, means projecting from said strut for removably securing said cover plate in position, a multiplicity of apertures formed in said top plate and said cover plate for providing ventilation for the 15 interior of said base and sheets of perforate material secured in place above and below said movable unit by said insulating ring and cover plate respectively.

WILLIAM A. HARVEY.
